MATERIAL-HANDLING APPARATUS

Charles W. Ruth, Baltimore, Md., assignor to
 Western Electric Company, Incorporated, New
 York, N. Y., a corporation of New York

Application September 9, 1950, Serial No. 184,073

8 Claims. (Cl. 294—103)

1

This invention relates to material-handling apparatus, and more particularly to grapples for engaging and lifting solid materials of various sizes.

There are innumerable instances in industry where solid materials are stacked in storage, and it is necessary for this material to be picked up by some such agency as a traveling crane to be transported to and deposited at some point of use or consumption. Thus, to give a particular illustration, in the manufacture of electrical cables covered with an extruded lead or lead alloy sheath, one or more kettles may be located near a plurality of extrusion presses for melting and supplying molten metal to the presses. The metal to be melted will ordinarily be stored in the form of pigs at a nearby point, and will be transported in batches by a traveling crane and a conveyer, as required, from that point to the several kettles.

An object of this invention is to provide new and improved material-handling apparatus.

A further object of the invention is to provide new and improved grapples for handling articles of various sizes.

Another object of the invention is to provide a simply constructed, sturdy and reliable grapple which may be used in conjunction with a hoist or crane for engaging and lifting articles, such as pigs of metal, particularly where such pigs of metal may be used in different standard sizes for different operations.

With these and other objects in view, an apparatus illustrating certain features of the invention may comprise a pair of relatively movable jaws, means for lifting said jaws and means actuated by the lifting means for imparting straight-line reciprocatory movement to open and close the jaws.

Other objects and features of the invention will clearly appear from the following detailed description of an apparatus forming specific embodiments thereof, when read in conjunction with the accompanying drawings, in which:

Fig. 1 is a side elevation view of a pig metal grapple constructed in accordance with the invention and shown secured to a traveling crane under operating conditions;

Fig. 2 is a plan elevation view of the grapple illustrated in Fig. 1, with portions of the guideways broken away;

Fig. 3 is a vertical sectional view taken along the lines 3—3 of Fig. 2, looking in the direction of the arrows;

Fig. 4 is a sectional view corresponding with Fig. 3, but with the grapple jaws secured in open positions;

Fig. 5 is a perspective view of the grapple illustrated in Fig. 2, with a portion of a guideway broken away, and

Fig. 6 is a cross-sectional view corresponding with Fig. 4, of an alternate embodiment of the device.

2

Referring now to the drawings, and more particularly to Fig. 1, a grapple 10 is adapted to be secured to a traveling electric hoist 11 and its depending pulley 12, which travel on an overhead transverse track 13 and a pair of longitudinal tracks 14—14. A switch 15, which is secured to a depending cable 16, permits an operator to control the electric hoist 11 in a convenient manner. Metal pigs 17—17 may be stored at a depot 18 from which they may be taken in a batch 19, elevated and placed upon a conveyer 20 for transportation to a melting kettle (not shown).

The embodiment of the grapple illustrated in Figs. 2 through 5, includes a pair of parallel frame members 21—21 having U-shaped guideways 22—22 for receiving a pair of rollers 23—23 which are adapted to rotate on the extremities of a transversely reciprocable shaft 24. An elongated L-shaped fixed jaw 25 is secured to and dependent from one end of the frame members 21—21, and a cooperating elongated L-shaped movable jaw 26 is dependent from and is secured to the shaft 24 by a plurality of supporting members 27—27. A metal lifting ring 28, which is adapted to be engaged by the pulley 12 of the electric hoist 11, is associated with the fixed jaw 25 and the movable jaw 26 by a toggle mechanism comprising a first pair of angular linking arms 29—29 and a second pair of angular linking arms 30—30, each of which is journaled upon a shaft 31 which serves as a pivot point for the toggle mechanism and is secured to the metal ring 28 by a bracket 32 and a pair of nuts 33—33. The second pair of linking arms 30—30 are journaled upon the shaft 24, and the first pair of linking arms 29—29 are journaled upon a fixed shaft 34 secured to the parallel frame members 21—21 at points 35—35. The fixed shaft 34 also cooperates with a cross-bar 36 located at the opposite end of the frame members 21—21 to secure the frame members 21—21 in spaced parallel relation.

Other structural features of the device are designed to control the movements of the movable jaw 26. A pair of triangular stops 37—37 are adapted to bear against the lower surfaces of the frame members 21—21 to nullify any tendency of the movable jaw 26 to rotate in a counterclockwise direction when the grapple is carrying a load. In an analogous manner, the ends of a shaft 38, which extend through and is secured to the supporting members 27—27, travel within the guideways 22—22 and thus compensate for any tendency of the jaw 26 to rotate in clockwise direction.

The movable jaw 26 may be secured in an extended, open jaw position at its end of the frame members 21—21, by a latch mechanism comprising a pair of arms 39—39 having a pair of hooks 40—40 which are adapted to engage the shaft 24, which is secured to the jaw 26. The

latch arms 39—39 are secured to each other by a latch bar 41, and the entire latch mechanism is pivotally secured to the frame cross-bar 36 by a shaft 42 which is journaled within a plurality of trunnions 43—43 secured to the cross-bar 36. A guide-bar 44, which is secured to the ends of the frame members 21—21 just above the cross-bar 36, is provided to assist the operator in grasping the latch-bar 41 and to assist in controlling horizontal movements of the 10 grapple when it is in an elevated position.

Operation

In the operation of the device, the grapple 10 may be used to transfer the batch 19 of metal pigs 17—17 from the storage depot 18 of such pigs 17—17 onto the conveyor 20 for transportation to a melting kettle (not shown), which supplies a cable sheathing press (not shown), as is illustrated in Fig. 1. As the electric hoist 11 lowers the grapple 10 over the metal pigs 17—17 in the storage depot 18 preparatory to picking up a load, the fixed jaw 25 and the movable jaw 26 will normally be secured in an extended open jaw portion, as is illustrated in Fig. 4. In this position, the rollers 23—23 will have traveled in the guideways 22—22 of the frame members 21—21 until the jaw 26 and its associated shaft 24 are at the extremities of the frame members 21—21, where the shaft 24 has become engaged by the latch hooks 40—40.

The electric hoist 11 and the guide-bar 44 are then employed to position the grapple 10 over the top layer of the metal pigs 17—17 with the fixed jaw 25 engaging the lips of the pigs 17—17. To close the jaws 25 and 26 upon the metal pigs 17—17, the operator pulls the latch-bar 41 toward the guide-bar 44 causing the latch hooks 40—40 to become detached from the transversely reciprocable shaft 24 thus releasing the movable jaw 26, after which the operator actuates the electric hoist 11. As the hoist 11 elevates the pulley 12, the jaws 25 and 26 are drawn together by the toggle action of the angular linking arms 29—29 and 30—30 pivoting upon the shaft 31, whereby the movable jaw 26 travels toward the fixed jaw 25 with a straight line motion which is controlled by the rollers 23 of the reciprocable shaft 24 traversing the guideways 22—22 of frame members 21—21, until the jaws 25 and 26 assume the closed and loaded position illustrated in Fig. 3.

In releasing a load, it is merely necessary to actuate the electric hoist 11 to lower the pulley 12 until the load, such as a batch 19 of metal pigs 17—17 is resting upon a solid surface, such as the conveyor 20. As the frame members 21—21 are thus supported, continued downward motion of the metal ring 28 will automatically cause the jaws 25 and 26 to open by the toggle action of the angular linking arms 29—29 and 30—30, which pivot upon the shaft 31. Since the pair of the linking arms 29—29 is journaled upon the fixed shaft 34 at one extremity of the frame members 21—21 and the pair of linking arms 30—30 is journaled upon the transversely reciprocable shaft 24, which is secured to the movable jaw 26, the jaw 26 will be urged toward the opposite extremity of the frame members 21—21, being guided by the rollers 23—23 on the ends of the shaft 24 traveling within the guideways 22—22, until the shaft 24 passes under the latch arms 39—39 and becomes engaged by the latch hooks 40—40. The operator completes the releasing operation by applying a hor-

izontal force to the guide-bar 44 to move the fixed jaw 25 away from the lips of the metal pigs.

Alternate embodiment

In an alternative embodiment of the device, illustrated in cross-section in Fig. 6, a frame member 121 is provided with a U-shaped guideway 122 for receiving a pair of elongated L-shaped movable jaws 125 and 126. The jaws 125 and 126 are secured to a metal lifting ring 128 by a toggle mechanism comprising an angular linking arm 129 and an angular linking arm 130, which are mutually pivotally secured to the metal ring 128 by a shaft 131 and a bracket 132. The linking arm 129 is journaled upon a transversely movable shaft 134, which is secured to the movable jaw 125, and the linking arm 130 is journaled upon a transversely movable shaft 124, which is secured to the movable jaw 126. Like members shown in cross-section in Fig. 6 and described herein, have corresponding members not shown, as in the case of Fig. 4.

A cross-bar 136 serves to retain the frame member 121 in parallel spaced relation with the corresponding frame member which is not shown in the cross-sectional view of Fig. 6. The cross-bar 136 also acts as a stop to prevent the movable jaw 126 from traveling beyond the ends of the frame members. In a similar manner, a cross-bar 145 functions as a stop for the movable jaw 125 and cooperates with the cross-bar 136 in securing the frame members in spaced parallel relation. The jaw 126 may be secured against the stop member 136 by a latch arm 139, which is pivotally secured to the member 136 and has a hook 140 for engaging the transversely movable shaft 124. A latch arm 148 having a hook 149 is similar in construction to the latch arm 139 and the hook 140, and serves to secure the jaw 125 against the cross-bar 145 by engaging the movable shaft 134.

An interior stop member 146 is secured within the guideway 122 near the center portion of the frame member 122 to control the inward movement of the jaw 125. In a similar manner, a stop member 147 limits the motion of the jaw 126. By limiting the inward movement of the jaws 125 and 126, the stop members 146 and 147 prevent the entire frame from becoming unbalanced when the grapple is in an elevated position.

Operation of alternate embodiment

In the operation of the alternative embodiment of the device, after the hook members 140 and 149 have released the shafts 124 and 134, the jaws 125 and 126 may be drawn toward each other by the toggle action of the lifting ring 128 and the pivoted linking arms 129 and 130, the movement of the jaws 125 and 126 being limited to a straight-line by the guideway 122. The toggle mechanism acts upon both movable jaws, instead of upon one movable jaw and the frame as in the case of the preferred embodiment of the device. It is readily apparent that the operation of the alternative form of the device having both jaws movable, is in other respects substantially the same as the operation of the preferred embodiment of the invention wherein one of the jaws is fixed.

The advantages of the grapples herein disclosed are manifest upon consideration of their ease of operation and simplicity of construction. The straight-line reciprocatory type action of the gripping jaws is particularly suitable for use

in engaging slab-like objects of varying lengths, such as pigs of metal. Moreover, during such straight-line motion the lips of the gripping jaws remain constantly parallel to each other. It is evident that such parallel relationship assures a positive gripping action when metal pigs are handled, without the danger of having loads slip from the jaws, which is attendant in using a grapple in which one or both jaws pivot during an arcuate opening and closing motion.

What is claimed is:

1. A grapple comprising a frame, a fixed jaw and a cooperating movable jaw mounted on said frame, means mounted on the frame for guiding the movable jaw in a straight-line reciprocatory motion toward and away from the stationary jaw, lifting means located above the frame, and toggle means secured to the lifting means for actuating the movable jaw comprising a first link and a second link mutually pivotally secured to the lifting means, said first link also being secured pivotally and directly to the frame and said second link also being secured pivotally and directly to the movable jaw, whereby actuation of the lifting means imparts relative straight-line motion to the movable jaw to open and close the jaws.

2. A grapple comprising a frame, a fixed jaw and a movable jaw mounted on said frame, means mounted on the frame for guiding the movable jaw in a straight-line reciprocatory motion toward and away from the stationary jaw, means mounted on the movable jaw for maintaining said movable jaw at a constant angle with respect to the fixed jaw, lifting means located above the frame, and a pair of links connected pivotally together to the lifting means, the free ends of the links being pivotally connected directly to the frame and the movable jaw.

3. A grapple comprising a frame, a fixed jaw and a cooperating movable jaw mounted on said frame, means mounted on the frame for guiding the movable jaw in a straight-line reciprocatory motion toward and away from the fixed jaw, means mounted on the movable jaw for maintaining said movable jaw at a constant angle with respect to the fixed jaw, lifting means located above the frame, toggle means secured to the lifting means for actuating the movable jaw comprising a first and a second link mutually pivotally secured to the lifting means, said first link also being pivotally and directly secured to the frame and said second link also being pivotally and directly secured to the movable jaw whereby actuation of the lifting means imparts relative straight-line motion to open and close the jaws, and means mounted on the frame for securing the jaws in an open position.

4. A grapple comprising a pair of spaced parallel frame members, an elongated L-shaped fixed jaw secured to one end of said frame members, a cooperating elongated L-shaped relatively movable jaw mounted on the frame members, means mounted on the frame members for guiding the movement of the movable jaw in a straight-line reciprocatory motion toward and away from the fixed jaw, means carried with the movable jaw for maintaining the movable jaw at a constant angle with respect to the fixed jaw, lifting means positioned above the frame members, linkage means secured to the lifting means for actuating the movable jaw comprising a first and a second link mutually pivotally secured to the lifting means, said first link also being pivotally and directly secured to the frame

and said second link also being pivotally and directly secured to the movable jaw whereby actuation of the lifting means imparts relative straight-line motion to open and close the jaws, and a latch pivotally secured to one end of said frame members for retaining the movable jaw in an open position.

5. A grapple, which comprises a pair of channels, means securing the channels rigidly in parallel positions, an L-shaped jaw depending from the channels in a position extending transversely to the channels and secured against pivotal movement with respect to the channels, a pair of carriages mounted for movement along the channels, a second jaw secured to the carriages, a clevis, a link pivotally secured at one end with respect to the first-mentioned jaw and pivotally secured at the other end to the clevis, and a second link pivotally secured at one end directly to the second-mentioned jaw and pivotally secured at the other end directly to the clevis and the other link.

6. A grappling device, which comprises a guideway, a jaw mounted on the guideway, a second jaw mounted slidably on the guideway toward and away from the first-mentioned jaw, means secured to the jaws preventing pivotal movement between the jaws and the guideway, a link secured pivotally at one end to the first-mentioned jaw, a second link secured pivotally at one end to the second-mentioned jaw, and hoisting means securing the other ends of the links pivotally together to form a linkage therewith.

7. A grappling device, which comprises a guideway, a jaw fixed rigidly to the guideway at one end thereof, a second jaw mounted slidably on the guideway toward and away from the first-mentioned jaw, means secured to the second jaw preventing pivotal movement between the second jaw and the guideway, a link secured pivotally at one end to the guideway, a second link secured pivotally at one end to the second jaw, and hoisting means securing the other ends of the links pivotally together to form a linkage therewith.

8. A grapple, which comprises a pair of channels, means securing the channels rigidly in parallel, oppositely facing positions, an L-shaped jaw depending from the channels in a position extending transversely to the channels and secured rigidly to the channels, a pair of carriages mounted for movement along the channels, a second jaw secured to the carriages, a clevis, a link secured at one end pivotally with respect to the first-mentioned jaw and secured pivotally at the other end to the clevis, and a second link secured at one end pivotally to the second-mentioned jaw and secured at the other end pivotally to the clevis and the other link.
